(57) **CLAIM**

The ornamental design for a vibrating plate, as shown and described.

DESCRIPTION

FIG. 1 is a front right perspective view of the vibrating plate showing our new design, with the handle in down position;

FIG. 2 is a back left perspective view thereof;

FIG. 3 is a back view thereof;

FIG. 4 is a left side view thereof;

FIG. 5 is a front view thereof;

FIG. 6 is a right side view thereof;

FIG. 7 is a top view thereof;

FIG. 8 is a front left perspective view of the vibrating plate showing our new design, with the handle in up position;

FIG. 9 is a back view thereof;

FIG. 10 is a left side view thereof;

FIG. 11 is a front view thereof;

FIG. 12 is a right side view thereof;

FIG. 13 is a top view thereof; and,

FIG. 14 is a bottom view thereof.
